UNITED STATES PATENT OFFICE.

WALTER T. FAIRALL, OF STOCKTON, CALIFORNIA, ASSIGNOR TO W. H. FAIRALL, OF GLENDALE, CALIFORNIA.

BURGLAR-ALARM ATTACHMENT FOR WINDOWS AND DOORS.

Application filed February 9, 1926. Serial No. 86,991.

This invention relates to improvements in burglar alarm devices, my principal object being to provide a means for enabling an alarm device such as is shown in my 5 Patent No. 1,467,363, to be permanently mounted in connection with a door or window, and which will enable said door or window to be kept closed or to be opened a sufficient distance to provide ventilation, 10 while still effecting protection against an intruder further opening the door or window sufficient to permit him to enter, and without marring the woodwork.

A further object of the invention is to 15 arrange such means in the form of an attachment readily applied to the parts to be safeguarded, and which permits the alarm device to be readily disassociated from one movable member or the other so as to permit the door or window functioning in the usual manner when desired and without any interference.

A further object of the invention is to produce a simple and inexpensive device 25 and yet one which will be exceedingly effective for the purpose for which it is designed.

These objects I accomplish by means of such structure and relative arrangement of parts as will fully appear by a perusal of 30 the following specification and claims.

In the drawings similar characters of reference indicate corresponding parts in the several views:

Fig. 1 is a fragmentary outline of a pair 25 of ordinary sash windows in their closed position showing my alarm device and its attachment means applied thereto.

Fig. 2 is a fragmentary cross section of 40 the windows partly open showing my structure applied thereto in holding position.

Fig. 3 is an enlarged fragmentary view of a catch plate and the cooperating tongue on one end of the alarm device.

Referring now more particularly to the 45 characters of reference on the drawings, the alarm device itself is preferably identical with that shown and covered in the above mentioned patent and consists essentially of a tubular barrel 1 with another barrel 2 telescopically mounted therein for limited 50 sliding movement. The barrel 1 is provided with a slot 3 adjacent one end to receive a blank cartridge, which as fully set forth in said patent, explodes when said barrels are moved toward each other to their limit.

For permanently mounting this device in connection with the lower one of an ordinary pair of sash windows, I provide an angle bracket plate 4 adapted to rest against the top horizontal face and the inner adjacent vertical face of the upper frame 5 of said lower window 6 near one side edge thereof, and to be secured by screws 7 passed through the two faces of said plate.

Ears 8 project outwardly from the vertical member of the plate 4 to form bearings for a pin 9 passed through the lower end of the barrel 1, said barrel projecting between the ears.

This pin may be permanently mounted or 70 removable, as may be desired.

The upper end of the barrel 2 is provided with a rigid flat tongue 10 which projects therebeyond for a certain distance, and is then bent at a predetermined angle to project toward the upper window 11. A vertical flat plate 12 is placed against the vertical side frame 13 of said upper window in alignment with the bracket plate 4, and is held in place by screws 14. This plate has 75 a plurality of vertically spaced transverse slots 15 transversely aligned with the outer end of the tongue.

This plate is so disposed that when the windows are closed as shown in Fig. 1, the 85 tongue 10 when the barrels are in their normally slack relation, will engage the lowermost slot. This arrangement enables the upper window to be lowered or the lower window to be raised a distance equal to the 90 space between the end-most slots, and still enable the tongue to be engaged with a slot and the window thus held from further opening.

In order to prevent the tongue from possibly being jarred out of a slot the horizontal faces of the tongue at their outer ends 95 preferably flare outwardly somewhat as shown at 16, while the slots are undercut as at 17.

In operation it will be evident that when the device is thus positioned and the tongue is engaged with any slot, a pressure exerted to further lower the upper window or raise the lower window will cause the barrels of 105 the alarm device to telescope into each other, causing the cartridge to be exploded. Even if the cartridge is omitted however, the device serves as a sufficient check against opening of the window, since the barrels can only 110

telescope a limited amount and then become a rigid immovable unit. It will be noted that when the pressure thus applied to the window is imparted to the plate 13 and bracket 4, the strain on the various screws is a shearing rather than a tensional one. There is therefore no tendency for the screws to pull out of the wood and render the device inoperative.

19 When the device is not in use the tongue is disengaged from the plate-slot and the alarm device is turned down on its pivotal pin 9, as shown in dotted lines in Fig. 2 so that it will hang down alongside the lower window frame.

If the pin 9 is removable the alarm device itself may be removed at any time without disturbing the bracket and slotted plate.

Though I have shown the device as used 20 in connection with sash windows, it may be used with equal efficiency in connection with casement and other windows, as well as with doors.

In the latter case the bracket for the 25 alarm device is flat as shown in the previous patent, and the slotted plate would be mounted on the floor inwardly of the door in line with the tongue on the device.

From the foregoing description it will be 30 readily seen that I have produced such a device as substantially fulfills the objects of the invention as set forth herein.

While this specification sets forth in detail the present and preferred construction 35 of the device, still in practice such deviations from such detail may be resorted to as do not form a departure from the spirit of the invention, as defined by the appended claims.

40 Having thus described my invention what I claim as new and useful and desire to secure by Letters Patent is:

1. A burglar alarm and check attachment 45 for relatively movable members including with an alarm device, a bracket pivoted onto one end of the device and adapted to be

mounted onto one member, a plate having a transverse slot adapted for attachment to the other member in alinement with the device, said device normally sloping from its 50 pivoted end toward the plate at an acute angle thereto, and a tongue for detachable engagement with the slot, mounted on the end of the device opposite to the bracket, said tongue lying substantially at right 55 angles to the slot and plate, whereby to prevent movement of the movable member in either direction when the tongue is in the slot.

2. A burglar alarm and check attachment 60 for relatively movable members including with an alarm device, a bracket pivoted to one end of said device and adapted to be mounted onto one member, a plate having a slot adapted for attachment to the other 65 member in alinement with said device, and a tongue on the end of the device opposite to the bracket for detachable engagement with the slot, the horizontal faces of the slot having an inward diverging slant and the 70 corresponding faces of the tongue having an outward flare, whereby to prevent accidental displacement of the tongue from the slot when engaged therewith.

3. A burglar alarm and check attachment 75 for windows comprising with an alarm device, a plate having a slot arranged to be fixed on the frame of the upper window, a member on one end of the alarm device for engagement with the slot, a bracket for attachment to the lower window frame in alinement with the plate, and a pivotal connection between the bracket and the other 80 end of the alarm device; said pivotal connection being so located with respect to the inner face of the lower window frame as to permit said alarm device to be turned down to lie vertically along said frame when said member is disengaged from the slot.

In testimony whereof I affix my signature.

WALTER T. FAIRALL.
